UNITED STATES PATENT OFFICE

FRED S. BOLTZ, OF MANSFIELD, MASSACHUSETTS.

CLOTHES CONTAINER.

Application filed July 31, 1925. Serial No. 47,241.

The invention relates to a new and useful improvement in clothes container for use in laundries, dye establishments and the like for use in holding and delivering soiled clothes to the wash wheel or delivering to the dyeing machine clothes to be dyed. It is especially intended to provide such a device to be hung to a trolley or other overhead support.

10 The invention will be fully understood from the following description when taken in connection with the accompanying drawings and the novel features thereof will be pointed out and clearly defined in the claims 15 at the close of this specification.

In the drawings:

Fig. 1 is a side elevation of a device embodying the invention shown as hung from an overhead trolley and in operative position 20 for delivering the goods to the wash wheel.

Fig. 2 is a front elevation of the device embodying the invention shown in Fig. 1, the wash wheel being omitted.

Fig. 3 shows the container tipped into position to run the nose further into the wash wheel than shown in Fig. 1.

Referring to the drawings:

There is shown at 10 the container mounted on trunnions 11, 11 projecting from cross bars 9 on opposite sides of the container, said trunnions being journaled in the yoke shaped frame 12 which has a swivel or turn-table connection at 13 with a bar 14 to which are secured upwardly extending forked bearing members 15 in which are journaled trolley wheels 16 running on an overhead track 17.

40 The container 10 is hung off its centre of gravity by the trunnions so located that normally it will have a slight pitch as shown in full lines in Fig. 1, to hang clear of the wash wheel 18 and thereby enable the operator to load the clothes into the container more easily. There is shown at 18 a wash wheel having a receiving opening 19 for the goods. The container is hung so that its delivery opening 20 will be adjacent the inlet opening 19 to the wash wheel.

50 The container is provided with a bottom which is preferably curved downwardly and outwardly, forming a convex heel portion 21 as shown in Fig. 1. The delivery opening 20 is located in the side near the bottom and toward the wash wheel. There is provided 55 a movable closure member 22 which is adapted to close the opening 20 and is provided

with means for moving the closure member so as to open the delivery outlet. The lower part of the container is formed with a forwardly extending nose portion 23 which, 60 when the container is moved into position for delivering clothes in the wash wheel, will extend through the inlet opening 19 into the interior of the wash wheel. Nose portion 23 acts as a ram swinging on trunnions 65 11 if the soiled clothes need packing into the wash wheel.

The closure member 22 is rigidly mounted upon one end of an arm 24, the other end of said arm being fast to a shaft 25 journaled 70 in bearings 26, 26 in the side of the container. An operating lever 27 provided at one end with a clutch member 28 is mounted loosely on the shaft 25 in such manner that it is both rotatable and slidable axially 75 on said shaft. Said clutch member 28 is provided with teeth which are adapted to engage with teeth on a clutch member 29 mounted fast on the shaft 25. In Fig. 2 the said clutch members are shown disengaged from each other. By means of the lever 27 the clutch member 28 may be moved into engagement with the clutch member 29 at will so that by rocking said lever 27, the shaft 25 may be rocked in its bearings and 80 thereby operate the closure member 22 to open and close the opening 20 in the container. When the operating lever 27 is in the position shown in full lines in Fig. 1, the closure member 22 will be in closing position. By pulling the lever 27 downwardly the end of the arm 24 connected with the closure member will be rocked upwardly in 85 to the dotted line position shown in Fig. 1, thereby raising the closure member 22. 90 95

Secured to the opposite ends of the closure member 22 are the flange members 30 which, when the closure member 22 is in closed position extend up respectively on the outside of the side walls of the container 10 so as 100 to close the opening 20 at the sides something after the manner of the flange on a box cover, a portion of the closure member 22 being inside of the sides of the nose member 23. In the preliminary part of the 105 operation of discharging the goods from the container into the wash wheel, the lever 27 will be operated to adjust the nose of the container into the position shown in dotted lines in Fig. 1.

When the wash wheel has become nearly 110 filled with the goods so that they begin to

crowd, then by means of the lever 27 the container can be jiggled back and forth to thrust the nose member 23 farther into the wash wheel as shown in Fig. 3 so as to ram 5 the mass of goods therein farther into the container and pack them more closely.

Means are provided whereby the container may be held against swiveling movement. The means shown are as follows:

- 10 10 A bolt 31 is slidably mounted in bearings 32, 32 formed in lugs attached to the side of the yoke 12, said bolt being normally held by a spring 33 in engagement with a bolt hole 34 in the supporting member 14 15 from which the container is hung. A pull string or wire 35 is connected with the lower end of the bolt 31 so that by pulling down on the said pull member 35 the bolt may be withdrawn from its locking position and 20 thereby permit the container to be turned on its swivel into proper position relative to the inlet opening in the wash wheel.

A window 36 is provided in one side of the container to permit the operator to view the 25 inside to ascertain when all the clothes have been removed from the container. This window may be of transparent material or may be of wire netting or any other suitable material.

- 30 30 Preferably a chain 37 or other suitable flexible connection is attached to one side of the container having a hook 38 at one end so as to enable the container to be hooked up with another container alongside of the same 35 so that by making the wash wheel 18 of sufficient length and divided into compartments the two containers may be operated at the same time.

The swivel connection 13 at the top of the 40 container permits the container to be swung around to bring the container into operative position with relation to the entrance to the wash wheel which is usually stationary. If the device is used for delivering goods to 45 a dye vat, the vat will be substituted for the wash wheel 18 having an inlet opening and the operation will be the same as already described for use with a wash wheel.

What I claim is:

- 50 50 1. A container for goods for delivery to a wash wheel or other receptacle, said container being pivotally suspended at one side of its centre of gravity in such manner as to normally hang in an inclined position and having an opening in one side at the lower end, a closure member for said discharge opening and a lever having operative connection with said closure member whereby said closure member may be opened and closed.

2. A container for goods for delivery to a wash wheel or other receptacle, said container being pivotally suspended and having an opening in one side at the lower end, a closure member for said discharge opening

and a rotary shaft mounted transversely of said container at one side thereof, an arm rigidly connected at one end with said closure member and at its other end connected with a clutch member loosely mounted on 70 said shaft so as to be both rotatable and slideable axially thereon, a cooperating clutch member rigidly mounted on said shaft, an operating lever connected with said first clutch member whereby said first clutch 75 member may be moved into operative engagement with the fixed clutch member and whereby when so engaged the said lever may be operated to rotate said shaft and thereby open or close at will said closure member. 80

3. A container for goods for delivery to a wash wheel or other receptacle, said container being pivotally suspended and having an opening in one side at the lower end, a closure member for said discharge opening, 85 a rotary shaft, an arm rigidly connected at one end with said closure member and at its other end connected with a clutch member loosely mounted on said shaft so as to be both rotatable and slideable axially thereon, 90 a cooperating clutch member fixed on said shaft, an operating lever connected with said first clutch member whereby said first clutch member may be moved into operative engagement with the fixed clutch member and whereby when so engaged the said lever may be operated to rotate said shaft and thereby open or close at will said closure member, said closure member being formed with flanges on its ends which, when the closure 100 member is closed, extend up on the sides of the container at the edges of said opening.

4. A container for goods for delivery to a wash wheel or other receptacle, said container being pivotally suspended and having an opening in one side at the lower end, a closure member for said discharge opening and a rotary shaft mounted transversely of said container at one side thereof, an arm rigidly connected at one end with said closure member and at its other end connected with a clutch member loosely mounted on said shaft so as to be both rotatable and slideable axially thereon, a cooperating clutch member rigidly mounted on said shaft, an operating lever connected with said first clutch member whereby said first clutch member may be moved into operative engagement with the fixed clutch member and whereby when so engaged the said lever may be operated to rotate said shaft and thereby open or close at will said closure member, the lower end of the container being formed with a nose extension below the opening which is adapted to be projected into the 120 opening in the receptacle into which the goods are to be delivered when the container is in operative position.

5. A container for goods for delivery to a wash wheel or other receptacle, said con- 130

- tainer being pivotally suspended and having an opening in one side at the lower end, a closure member for said discharge opening, a pivoted lever having operative connection with said closure member whereby said closure member may be opened and closed, an overhead supporting member and a swivel connection between said container and said overhead support. 5
- 10 6. A container for goods for delivery to a wash wheel or other receptacle, said container being pivotally suspended and having an opening in one side at the lower end, a closure member for said discharge opening, a pivoted lever having operative connection with said closure member whereby said closure member may be opened and closed, an overhead supporting member and a swivel connection between said container 15 and said overhead support, said overhead supporting member being provided with a hanger carrying trolley wheels which permit the container to be hung from and moved on an overhead track. 20
- 25 7. A container for goods for delivery to a wash wheel or other receptacle, said container being pivotally suspended and having an opening at or near the lower end, a closure member for said discharge opening and a pivoted lever having operative connection with said closure member, whereby said closure member may be opened and closed, said container being provided with a window in one of the side walls thereof. 30
- 35 8. A container for goods for delivery to a wash wheel or other receptacle, said container being pivotally suspended and having an opening at or near the lower end, a closure member for said discharge opening, a pivoted lever having operative connection with said closure member, whereby said closure member may be opened and closed, said container being formed with a forwardly extending nose below the opening, said nose being adapted to be projected into the opening in the receptacle into which the goods are to be delivered. 40
- 45 9. A container for goods for delivery to a wash wheel or other receptacle, said container being pivotally suspended and having an opening at or near the lower end, a closure member for said discharge opening, a pivoted lever having operative connection with said closure member, whereby said closure member may be opened and closed, an overhead support, a swivel connection between said container and said overhead support, and a hanger mounted on said support having trolley wheels adapted to run on an overhead track. 50
- 55 10. A container for goods for delivery to a wash wheel or other receptacle, said container being pivotally suspended on a horizontal axis and having an opening in one side at the lower end, a closure member for said discharge opening, a pivoted lever having operative connection with said closure member whereby said closure member may be opened and closed, an overhead support, a swivel connection between said container and said support and a hanger mounted on said support having trolley wheels adapted to run on an overhead track. 60
- 65 11. A container for goods for delivery to a wash wheel or other receptacle, said container being pivotally suspended and having an opening at or near the lower end, a closure member for said discharge opening and means whereby said closure member may be opened and closed, said container being provided with a window in one of the side walls thereof. 70
- 75 12. A container for goods for delivery to a wash wheel or other receptacle, said container being pivotally suspended and having an opening at or near the lower end, a closure member for said discharge opening, means whereby said closure member may be opened and closed, said container being formed with a forwardly extending nose below the opening, said nose being adapted to be projected into the opening in the receptacle into which the goods are to be delivered. 80
- 85 13. A container for goods for delivery to a wash wheel or other receptacle, said container being pivotally suspended on a horizontal axis and having an opening in one side at or near the lower end, a closure member for said discharge opening, means whereby said closure member may be opened and closed, an overhead support, a swivel connection between said container and said support and a hanger mounted on said support having trolley wheels adapted to run on an overhead track. 90
- 95 In testimony whereof I affix my signature.
